HEAD REST

Karl Ramm, West St., Southington, Conn.

Filed July 9, 1959, Ser. No. 56,717

Term of patent 14 years

(Cl. D15—8)

Fig. 1 of the drawing shows a perspective view of the head rest showing my new design.

Fig. 2 shows a rear perspective view of the same.

The broken line representation of a seat back in Fig. 1 is shown for illustrative purposes only.

I claim:

The ornamental design for a head rest, substantially as shown and described.
